UNITED STATES PATENT OFFICE.

WILLIAM A. F. MACCALLUM, OF PHILADELPHIA, PENNSYLVANIA.

GOLF PRACTICE DEVICE.

Application filed January 25, 1928. Serial No. 249,240.

This invention generally stated relates to an amusement and instructive device particularly adapted for the use of golfers.

The leading object of the present invention is to provide a device of the character stated so arranged, constructed and connected that the golfer hitting the objective may determine whether the stroke in reality would have been a straight ball, a "slice" or a "pull."

The further object of the present invention is to provide movable visual means for determining whether the objective has been hit to produce a "slice" or the "pull."

Other and further objects of the present invention reside in the provision of general details of construction, arrangement and combination of parts for attaining the results sought by the foregoing objects.

The invention consists of the device hereinafter described and finally claimed.

The nature, characteristic features and scope of the invention will be more fully understood from the following description taken in connection with the accompanying drawings forming part hereof, and in which

Figure 1 is a view in plan with certain casing parts removed for better illustrative purposes.

Figure 2 is a bottom plan view of Figure 1 with certain casing parts removed.

Figure 3 is a detailed view hereinafter referred to.

Figure 4 is a view in longitudinal section taken upon line 4-4 of Figure 1.

Figure 5 is a view in cross section taken upon the line 5-5 of Figure 1.

Figure 6 is a view in cross section taken upon the line 6-6 of Figure 1.

Figure 7 is a view in cross section taken upon the line 7-7 of Figure 1.

Figure 8 is a view in cross section taken upon the line 8-8 of Figure 1 and

Figure 9 is a view hereinafter referred to.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail the reference numeral 1 designates a base plate usually of metal and which may be nailed or spiked to any appropriate surface as the ground or the floor in which connection the slots 2 are convenient for this purpose. The base 1 is provided with an incline 3 best seen in Figures 1 and 4. This incline 3 is used to guide the head of the golf club toward the objective 4, the latter preferably comprising a solid piece of rubber, and in practice represents a golf ball. This objective 4 is pivoted as at 5 to a frame 6 probably best seen in Figures 1 and 9, although it is shown in dotted lines in Figure 2. The object 4 is connected by means of a coil spring 7 as at 8 with the under side of the incline 3 as is clearly shown in Figure 4.

Thus, as the objective is hit the top or upper portion thereof is deflected forwardly against the spring 7, and after the club head has hit the objective and passes thereover the spring 7 retracts the objective 4. This is true whether the objective is hit squarely or is hit a glancing blow either to the left or the right. The forward end of the frame 6 is provided with a projection 9 which is adapted to move toward the left and the right beneath a plate 10 fixed to the base 1. This movement is possible because of the pivotal or swinging relation as at 11 of the frame 6 with the base 1. The frame 6 is connected at opposed sides with the coil springs 12 and 13 respectively which are arranged in parallelism with the coil spring 7 and are connected to the under side of the incline 3 as best seen in Figure 2. The frame 6 is afforded slight movement upon opposed plates 14 and 15 secured upon the base plate 1. The projection 9 is adapted in its lateral or crosswise movement to contact with direction indicators designated 16 and 17 respectively. These indicators 16 and 17 respectively are pivoted as at 18 to the casing 10 and are spring pressed as at 19. By this arrangement and construction of parts if the objective 4 is struck a glancing blow, which in a game of golf would amount to a "pull" the projection 9 contacts with the pivotal indicator 16 moves the same about its pivotal point so that the signal 22 which may be for instance the color red is moved before the opening 20 in plate 10. On the other hand, if the golfer hits the objective 4 a glancing blow, which in golf practice

90

95

100

105

110

would amount to a "slice," the signal 21 which might be black is moved before the opening 20 in plate 10, see Figure 6.

Thus, the golfer by the manner in which 5 said objective 4 is hit may determine whether the objective was hit to produce a straight ball, "pull" or a "slice," the advantages of which are apparent.

It is sometimes desirable that the base be 10 not rigidly fixed but be mounted to take care of rebounds. For this purpose the base may be provided with slotted ears 23 at each end of the base, these ears in turn may be provided with coil springs 24 attached to 15 ropes 25, the ropes in turn being secured to any desired fixture. The bottom of the base may be provided with cover plates 26 and 27 in order to protect coil springs.

Among the advantages claimed for the 20 above described device mention may be made of the following:

The indicator will positively disclose the manner of club swing. It will indicate if you are hitting the center of the objective 25 (ball) or on the right or left of it. Any blow off the center of the objective will send the latter off on a tangent, that is, when the indicator will "wink" at you. The indicator will enable the user to obtain the 30 proper stance, that is the distance to stand from the ball, position of feet in relation to ball, which is important in regard to hitting the ball fair. It will indicate if you are holding your club face properly in 35 relation to ball. It will show you, in swinging your club, if you "crab" your club at the wrist or shoulder, which means you are going to hit the ball with the heel or toe of your club. Above all, it will give you 40 confidence in yourself and make you act natural. In other words, it will make you feel that you can put them where you want them, and also gives you exercise you cannot obtain upon other golf devices on the market. 45 The device can be used anywhere there is room to swing a club.

What I claim is:

1. A device of the character stated comprising a base, a swiveled member upon said 50 base, an objective pivoted to said member, a central spring of relatively strong tension for maintaining said objective in neutral position, a spring of lesser tension upon each side of the objective spring and secured to 55 said member to permit pivotal movement in two directions only, and means indicative of swivel movement of said member.

2. A device of the character stated comprising a base, a swiveled member upon said 60 base, an objective pivoted to said member, a central spring of relatively strong tension for maintaining said objective in neutral

position, a spring of lesser tension upon each side of the objective spring and secured to 65 said member to permit pivotal movement in two directions only, and means including opposed visual parts indicative of swivel movement of said member.

3. A device of the character stated comprising a base, means for attaching said base 70 to place, a swiveled member upon said base, an objective pivoted to said member, a central spring of relatively strong tension for maintaining said objective in neutral position, a spring of lesser tension upon each 75 side of the objective spring and secured to said member to permit pivotal movement in two directions only, and means indicative of swivel movement of said member.

4. A device of the character stated comprising a base, a swiveled member upon said 80 base, an objective of solid rubber pivoted to said member, a central spring of relatively strong tension for maintaining said objective 85 in neutral position, a spring of lesser tension upon each side of the objective spring and secured to said member to permit pivotal movement in two directions only, and means indicative of swivel movement of said member.

5. In a device of the character stated comprising a base, a swiveled member upon said 90 base, an objective pivoted to said member, a central spring of relatively strong tension for maintaining said objective in neutral, 95 vertical position, a spring of lesser tension upon each side of the objective spring and secured to said member to permit pivotal movement in two directions only, and means indicative of swivel movement 100 of said member.

6. In a device of the character stated comprising a base, a swiveled member upon said 105 base, an objective pivoted to said member, a central spring of relatively strong tension for maintaining said objective in neutral position, a spring of lesser tension upon each side of the objective spring and secured to said member to permit pivotal movement in two directions only, and means simulating 110 eyes indicative of swivel movement of said member.

7. A device of the character stated comprising a base, a swiveled member upon said 115 base, an objective pivoted to said member, a central spring of relatively strong tension for maintaining said objective in neutral position, a spring of lesser tension upon each side of the objective spring and secured to said member to permit pivotal movement 120 in two directions only, and spring pressed means indicative of swivel movement of said member.

WILLIAM A. F. MACCALLUM.
